COMBINED BILLFOLD AND CALENDAR

Arthur Salm, Chicago, Ill., assignor to Arthur Salm Inc., Chicago, Ill., a corporation of Illinois

Filed July 18, 1960, Ser. No. 61,390

Term of patent 7 years

(Cl. D87—3)

Fig. 1.

Fig. 2.

Fig. 3.

FIG. 1 is a perspective view of a combined billfold and calendar in the partially open position and incorporating my new design;

FIG. 2 is a plan view of the inside faces thereof in the fully open position; and

FIG. 3 is a sectional view thereof taken on the line 3—3 of FIG. 2.

The remaining half of the outside face of the billfold and calendar is plain and unornamented and identical to the exposed outside face of FIG. 1. The essential features of the design reside in the portions shown in full lines.

I claim:

The ornamental design for a combined billfold and calendar, substantially as shown and described.
